HINGE

Richard G. Voge, Annapolis, Md.

Application April 1, 1935, Serial No. 14,145

10 Claims. (Cl. 16—164)

The hinge of the present invention while not exclusively confined thereto is particularly adapted to use on the doors of automobiles. It is especially intended for use as a concealed hinge, that is, one which when installed and in use is entirely hidden when the door is closed, no parts projecting either on the inside or outside. The hinge is especially adapted to use in constructions in which the vertical contour of the door or frame against which it fits is not straight but is curved. In such constructions it is desirable that when the door is open it be somewhat removed from the frame.

In the accompanying drawing Figure 1 is a front elevation of one form of closed hinge embodying the invention. Fig. 2 is a side elevation of the same. Fig. 3 is a transverse horizontal section along the line 3—3 of Fig. 1. Fig. 4 is a general perspective view from the inside showing an opened door provided with two hinges. Fig. 5 is a transverse horizontal section through a door and frame provided with a hinge of the present invention. Fig. 6 is a transverse vertical section of a door and frame provided with hinges of the present invention showing the door in an open position. Fig. 7 is a diagrammatic illustration to explain the construction and operation. Fig. 8 is a front elevation on a reduced scale of another form of closed hinge embodying the invention and Fig. 9 is a transverse horizontal section along the line 9—9 of Fig. 8.

The specific form of hinge illustrated comprises a member 10 which may be fastened to a frame and a member 11 which may be fastened to a door or vice versa. By means of a pintle 12 a link member 13 is fastened to the member 10 and by means of a pintle 14 a link member 15 is fastened to the member 11. As illustrated the outer end 16 of the member 13 is turned and the end 17 of the link member 15 is cut so as to fit the turned portion 16. Passing through the members 13 and 15 is a pintle 18. The pintles may be held in place in any suitable manner. For instance the pintles 12 and 14 may have drive fits in the members 10 and 11 and be more loosely engaged by the members 13 and 15 so that they may turn about the pintles or vice versa. The pintle 18 may have a drive fit in the member 15 and in addition may be provided with a pin 19 to aid in holding it in position. The pintle 18 may be more loosely engaged by the member 13 which may turn upon it and which may be held from coming off the pintle 18 by means of a threaded nut 20 at its end.

In Fig. 1 the extended or projected axes of the pintles are illustrated by means of dotted lines. It will be observed that when the axes of the pintles 12, 14, and 18 are projected or extended they meet in a single point P and it is of the essence of the present invention that the pintles be so arranged. The relative angles of the pintles may be varied within wide limits but they will always be so arranged that the projected axes of all three pintles meet in a point.

It is not essential that the members 13 and 15 lie in contact throughout their lengths but they may be conveniently brought into substantial contact with each other, and in order to allow easy swinging movement about the pintle 18 the adjacent surface of the member 13 may be curved to form a concave surface while the adjacent face of the member 15 may be curved to form a corresponding convex member as illustrated more clearly in Fig. 3. The meeting surfaces of the members 13 and 15 may conveniently form a conical surface with the axis of the pintle 18 forming the axis of the cone. This arrangement forms a complete and relatively snug fit.

As illustrated the three pintles 12, 14, and 18 are so arranged and constructed that their axes if prolonged would all intersect at the point P which is exterior and lying on the axis of desired rotation of the door in which the hinges are installed. In the specific hinge described, for simplicity of construction, in the closed position the axes of all three members lie in about the same plane and the axis of pintle 14 is a continuation of the axis of the pintle 12. This is not essential and other constructions or designs are possible providing in any case that the axes of all three pintles when projected intersect at a point.

In the hinge illustrated the pintles are arranged so that the axis of the pintle 18 is at an angle of 45° to the axis of the pintles 12 and 14. This permits a maximum opening of the door of 90° giving a working opening of approximately 80° since in the last 10° of movement of the hinge it works harder as it approaches its dead center. While the opening of 80° may be sufficient for ordinary use any desired less or greater angle of opening may be obtained by varying the angle of the axis of the pintle 18 to the axis of the other pintles.

As the door is opened the link members 13 and 15 swing on their respective pintles 12 and 14 and at the same time the member 13 will

turn about the pintle 18 through an arc determined by the extent of opening of the door.

The distance from the hinge to the axis upon which the door will rotate is determined by the relative location of the point P. This distance will ordinarily be several inches in order to remove or free the door from the curve of the body of the automobile. It will be understood of course that the smaller this distance is the less need will be for strength in the hinge and as this distance is made greater the elements of the hinge should be strengthened or made larger or stronger in any suitable manner.

In the form of the invention illustrated in Figs. 8 and 9 the frame members 10a and 11a may be adapted to extend across the entire width of the hinge. They may be made more or less triangular in shape so as to carry pintles 12a and 14a with their axes in a line but arranged at an angle to the sides of the hinge. The members 13 and 15 may be attached to these pintles and may be fastened together by a pintle 18a at right angles to the sides of the hinge members 13 and 15. In other respects the relations of the pintles may be the same as in the other figures. In this arrangement the abutting sides of the members 13 and 15 may be built flat as illustrated in Fig. 9, no curvature for clearance being needed. When this form of the invention is employed an angle of approximately 36° between the axes of the pintles will give a door opening of approximately 90°.

As illustrated in Fig. 5 the body frame member 21 of the car is provided with a cavity 22 for each hinge and the door frame member 23 is provided with a cavity 24. The sum of the depths of the two cavities 22 and 24 is about equivalent to the thickness of the hinge thus allowing the door when closed to come into close abutment with the frame member of the body. As illustrated the cavities 22 and 24 have each been made substantially equivalent in depth to one half the thickness of the hinge but any other suitable arrangement may be adopted. As illustrated in Fig. 5 it will be seen that the hinge may be entirely concealed leaving both exterior and interior of the body of the car clear and smooth with no projections.

As illustrated in Fig. 4 a door may be provided with two hinges, one above and one below the crest or maximum point of the arch of the body. This arrangement is preferable but not essential. Likewise there is illustrated a pair of hinges in Fig. 4 so placed as to fold in opposite directions, the upper hinge being illustrated with its pintle 18 below the attaching members 10 and 11 while the lower hinge is illustrated as having its pintle 18 above its attaching members 10 and 11. This is a convenient and desirable arrangement but is not essential.

When the member 10 of a hinge is secured to the frame of the car the axis of the pintle 12 permanently points toward the point P. As the hinge operates the relative relation of adjacent pintles cannot change. When the hinge is manipulated so as to swing the link member 13 about the pintle 12 it carries with it the pintle 18. Since the projected axis of the pintle 18 meets the point P it will always point toward P and remain at a fixed distance from the point P. As the link member 15 rotates about the pintle 18 the axis of the pintle 14 continues to point toward P and remains at a fixed distance from it. Therefore the member 11, or the door rigidly attached to it, is constrained to remain at a fixed

distance from point P and therefore to move on the surface of an imaginary sphere having P as a center. Fig. 7 is a diagram in which the line 25 illustrates the inner wall of a curved side of a device such as an automobile to which the door is to be hung. 26 illustrates the curved outer side of said wall. The line 27 indicates the projected axis of pintles 12 and 14 of an upper hinge. The line 28 indicates the projected axis of the pintle 18 of an upper hinge. The line 29 indicates the projected axis of the pintles 12 and 14 of a lower hinge. The line 30 indicates the projected axis of the pintle 18 of the lower hinge. The lines 27 and 28 meet at the point P1. The lines 29 and 30 meet at the point P2. As both upper and lower hinges are fixed also to the door any point D on the door originally abutting the frame is constrained by the upper hinge to move on the surface of an imaginary sphere having P1 as a center and the radius the distance from P1 to D. By the action of the lower hinge the point D on the door is also constrained to move on the surface of an imaginary sphere having P2 as a center with a radius equal to the distance from P2 to D. Therefore when controlled by both hinges it must move on the intersection of the two spheres which is a circle about the line P1, P2 and lying in a plane perpendicular to the line P1, P2. Therefore as every point on the door must move in a circle about P1, P2 the door will swing about P1, P2 as an axis. Since this axis may be arranged beyond the crest of the curve of the body the door will swing free of it as illustrated in Fig. 4.

It may be preferable to employ identical hinges at various points on the door as illustrated in Fig. 4 but this is not essential since it is not necessary that the hinges used with each other be the same size or shape.

Various changes in details may be employed in embodiments of the invention.

I claim as my invention:

1. Means for hinging a closure to swing about an exterior axis comprising two intermediate members, two end members, two pintles perpendicular to the axis each pivoting an intermediate member to a different end member, a pintle at an angle to the axis pivoting together the opposite ends of the intermediate members side by side the pintles being so positioned that their axes produced all meet in a point and all being in the same plane when the closure is closed.

2. In a hinge two end members, two intermediate members, a pintle pivoting the intermediate members to each other side by side, and pintles each of whose axis produced coincides with the axis of the other and pivoting each intermediate member to an end member, all the pintles being so arranged that their axes produced all meet at a point and all being in substantially the same plane.

3. A hinge which in closed position comprises a fastening member, a second fastening member beside the first fastening member, intermediate members connected together by a pintle at one end and at the other ends connected to the respective fastening members by means of pintles the axes of which are in a continuous line, all of the pintle axes being arranged to pass through a single point when produced.

4. A hinge comprising a pair of hinge plates, and a pair of hinge members each having a pivotal connection at one end to one end of an associated hinge plate, and with said pivotal connections offset so that they will be in axial 70 75

alignment when the hinge is closed, the free ends of said hinge members being pivoted to each other, and the pivotal axes at the two ends of each hinge member being disposed at an angle of substantially forty-five degrees to each other, with all three of the pivotal axes in said hinge passing through a common point in all relative positions of said hinge parts.

5. A hinge comprising a pair of hinge plates, and a pair of hinge members each having a pivotal side-by-side connection at one end to one end of an associated hinge plate, and with said pivotal connections offset so that they will be in axial alignment when the hinge is closed, the free ends of said hinge members being pivoted to each other, side by side, on a common hinge pin, and the pivotal axes at the two ends of each hinge member being disposed at an angle of substantially forty-five degrees to each other, with all three of the pivotal axes in said hinge passing through a common point in all relative positions of said hinge parts.

6. A hinge comprising a pair of hinge plates, and a pair of hinge members each having a pivotal connection at one end to one end of an associated hinge plate, and with said pivotal connections offset so that they will be in axial alignment when the hinge is closed, the free ends of said hinge members being pivoted to each other, with all three of the pivotal axes of said hinge passing through a common point in all relative positions of said hinge parts.

7. A hinge comprising a pair of hinge plates, and a pair of hinge members each having a pivotal side by side connection at one end of an

associated hinge plate, with said pivotal connections offset so that they will be in axial alignment when the hinge is closed, the free ends of said hinge members being pivoted to each other, side by side, on a common hinge pin, with all three of the pivotal axes in said hinge passing through a common point in all relative positions of said hinge parts.

8. In a hinge two end members, two intermediate members, a pintle pivoting the intermediate members to each other, and pintles each of whose axis produced coincides with the axis of the other and pivoting each intermediate member to an end member, all the pintles being so arranged that their axes produced all meet at a point and all being in substantially the same plane when the hinge is in closed position.

9. In a hinge two end members, two intermediate members, a pintle pivoting the intermediate members to each other, and pintles pivoting each intermediate member to an end member the axes of all the pintles being arranged to meet at a point when produced and all being in the same plane.

10. A hinge which in closed position comprises a fastening member, a second fastening member, intermediate members connected together by a pintle at one end and at the other ends connected to the respective fastening members by means of pintles the axes of which are in a continuous line, all of the pintle axes being arranged to pass through a single point when produced.
